(57) **CLAIM**

The ornamental design for a “bin and bay shelving and storage unit”, as shown and described.

DESCRIPTION

FIG. 1 is a perspective view of the bin and bay shelving and storage unit showing our design, in a first position.

FIG. 2 is a front side view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of the bin and bay shelving and storage unit showing our design, in a second position;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.
